UNITED STATES PATENT OFFICE.

WILLIAM G. ROBINSON, OF BATTLE CREEK, MICHIGAN.

COLLAR-HOLDING DEVICE.

1,079,024.

Specification of Letters Patent.

Patented Nov. 18, 1913.

Application filed March 14, 1910. Serial No. 549,369.

To all whom it may concern:

Be it known that I, WILLIAM G. ROBINSON, a citizen of the United States, and a resident of Battle Creek, in the county of 5 Calhoun and State of Michigan, have invented certain new and useful Improvements in Collar-Holding Devices; and I do hereby declare that the following is a full, clear, and exact description thereof, reference 10 being had to the accompanying drawings, and to the characters of reference marked thereon, which form a part of this specification.

This invention relates to a novel collar 15 holding device designed to be attached to the back of a collar in position for engagement with the usual guard pocket at the back of the neck band of the shirt to detachably fasten the collar to the band.

20 Among the objects of the invention is to provide a collar holding device by which the collar may be readily fastened to, and as readily detached from, the shirt neck band at the back thereof, and which will 25 occupy but little room from front to rear, and thereby avoid objectionable fullness or projection due to the use of an ordinary collar button.

30 A further object of the invention is to provide a collar holding device which may be quickly and readily attached to and detached from the collar, and so arranged that when attached to the collar is firmly locked thereto against accidental detachment.

35 As shown in the drawings:—Figure 1 is a perspective view of a collar provided with a holding device made in accordance with my invention. Fig. 2 is a fragmentary elevation of a collar, showing my holding 40 device or clip applied thereto. Fig. 3 is a rear elevation of the parts shown in Fig. 1. Fig. 4 is a perspective view of the holding device shown in Figs. 1 and 2, removed from the collar.

45 My improved holder comprises a tongue D adapted to lie against the inner side of the inner member of the collar A and two attaching arms, one at each side of the device and integral with the side members d of 50 the tongue. Each of the said attaching arms comprises an upwardly and outwardly inclined member d' which lies on the outer side of the inner member of the collar member A, and a downwardly and inwardly inclined member d² that lies on the inner side of the inner collar member A. Said

members d² terminate in rounded protuberances d⁴ to avoid catching in the band of the neck tie. The loop portions d³ of the said arms connecting said attached arm 60 members are turned obliquely inwardly toward the side members d of the tongue to constitute oblique shouldered portions which are adapted to be forced into holding engagement with the ends of the collar button 65 by the resiliency of the wire from which the device is formed.

In applying the device to the collar, the ends of the terminal members d² of the attaching arms are inserted through the button hole from the inner side of the inner collar member A and are forced downwardly therethrough until arrested by contact of the lower side of the collar button hole with the looped or closed portions d³ 70 of the arms between the members d' and d², or the position shown in Figs. 1 and 2. By reason of the inclination of the members d² of the attaching arm, the said attaching arms are sprung inwardly during the insertion of the members d² through the button hole, and again sprung outwardly when the device reaches its final position, with the looped or closed portions d² pressed outwardly, by the resiliency of the attaching 75 arms, against the ends of the button hole. When thus seated the turned-in portions d³ 80 constitute shoulders which prevent the device from being accidentally lifted and detached from the collar. The members d² are sprung inwardly toward each other to 85 spring said shouldered parts of the arms inwardly past the button hole ends to permit the device to be freely withdrawn and removed from the collar. 90

95 The device described is held in place by the resiliency exerted by the attaching arms, which attaching arms are located in part on one side of the collar and in part on the other.

100 It will be understood that the details of the device may be somewhat varied within the spirit and scope of the invention, and the invention is not limited to such details except as hereinafter made the subject of 105 the specific claim.

I claim as my invention:

110 A collar holding device made of a single piece of resilient wire, with a central part folded to form a centrally disposed loop-shaped tongue, the ends of the wire being folded upwardly exterior to the tongue to-

ward the closed end of said tongue and reversed upon themselves to constitute two-part spring arms, the terminals of which are adapted to be inserted through the collar button hole, the arms at their folded parts being spaced apart a distance greater than the width of said tongue and bent inwardly toward the tongue to form oblique shouldered portions which are forced into holding engagement with the ends of the

collar button hole by the resiliency of the wire.

In testimony, that I claim the foregoing as my invention I affix my signature in the presence of two witnesses, this 12th day of 15 March, A. D. 1910.

WILLIAM G. ROBINSON.
